(57) **CLAIM**

The ornamental design for a cell phone, as shown and described.

DESCRIPTION

Cell phone

The cell phone is used for communication and running programs.

Fig. 1.1 is a front elevation view of a cell phone showing our new design;

Fig. 1.2 is a rear elevation view thereof;

Fig. 1.3 is a left side elevation view thereof;

Fig. 1.4 is a right side elevation view thereof;

Fig. 1.5 is a top plan view thereof;

Fig. 1.6 is a bottom plan view thereof; and

Fig. 1.7 is a perspective view thereof.

Portions of the cell phone shown in broken lines form no part of the claimed design.

1 Claim, 7 Drawing Sheets
